VENDING APPARATUS

Andrew Geretta, Cleveland, Ohio

Original application March 7, 1935, Serial No. 9,772. Divided and this application July 11, 1935, Serial No. 30,869

6 Claims. (Cl. 194—58)

This invention relates to vending apparatus, and has for a principal object, the provision of new and improved apparatus of this character.

This application is a division of my copending application Serial Number 9,772, filed March 7, 1935, for Vending apparatus.

In the drawings accompanying this specification and forming a part of this application, I have shown, for purposes of illustration, one form 10 which my invention may assume, and in these drawings:

Figure 1 is a fragmentary perspective view of an embodiment of the invention, a portion of the housing being omitted to disclose the interior 15 construction of said embodiment,

Figure 2 is a fragmentary perspective detailed view of a portion of the invention,

Figure 3 is a horizontal sectional view substantially corresponding to the line 3—3 of Figure 4, 20 Figure 4 is a fragmentary vertical sectional view substantially corresponding to the line 4—4 of Figure 3,

Figure 5 is a fragmentary vertical sectional view substantially corresponding to the line 5—5 25 of Figure 3,

Figure 6 is a fragmentary vertical sectional view substantially corresponding to the line 6—6 of Figure 3,

Figure 7 is a fragmentary horizontal sectional view substantially corresponding to the line 7—7 30 of Figure 6,

Figure 8 discloses co-related perspective views of the match dispensing apparatus,

Figure 9 is a fragmentary vertical sectional 35 view of control mechanism employed in connection with the invention,

Figure 10 is a fragmentary perspective view of the under surface of the mechanism illustrated in Figure 9,

Figure 11 is an enlarged fragmentary top plan view of the coin controlled mechanism, shown in Figure 3, while

Figure 12 is an enlarged fragmentary vertical sectional view corresponding substantially to the 45 line 12—12 of Figure 11.

As shown in the drawings, the invention comprises a housing 26, somewhat larger at the bottom than at the top, and including a bottom wall 21, rear wall 22, top wall 23, side walls 24 50 and front wall 25, an upper portion 26 of the front wall 25 and side walls 24, together forming a closure hinged as at 27 to swing horizontally and adapted to be secured in closed position by a lock 28, the upper portion 26 being adapted when 55 closed to overlap the upper edge of the lower

portion 29 of the front wall 25, which is hinged, as at 30, to swing vertically, it being pointed out that when the upper portion 26 is in locked position, due to its overlapping relation with respect to the lower portion 29, the latter is held closed also, but when the upper portion 26 is unlocked and swung horizontally about its hinge, this releases the upper edge of the portion 29, which may then be swung downwardly about its hinge 30, thereby giving free access to the interior of the housing 26.

Mounted within the housing 26 are a pair of brackets 31 and 32, similar in construction except for their opposite disposition, and each having a laterally extending supporting shelf 33, 15 upon which is secured by any suitable means, a horizontally extending plate 34, adapted to support mechanism hereinafter described, the brackets 31 and 32 being spaced apart by the plate 34 so that they rest snugly against the 20 side walls 24 and 25 of the housing 26. The brackets 31 and 32 also have inwardly extending supporting shelves 35 to which are secured the end flanges 36 of a sheet metal support 37. The support 37 includes an elongated rear wall 38, 25 provided with a rearwardly extending top flange 39, and end walls 40, carrying the end flanges 36, and each of the end walls 40 (Figure 2), is provided with a projection 41 having a slot 42 adapted to register with a slot 63 in a front 30 bar 44, the support 37 and front bar 44, providing a rectangular frame, by which the article carrying parts are supported.

Disposed in each corner of the rectangular frame thus defined, are vertically arranged angle bars in end pairs, 45 and 46, and intermediate angle bars 47, in spaced groups of four, all of the angle bars being positioned and coordinated to define a plurality of article containing stacks 48. The lower ends of the angle bars 45, 46, and 47, are secured to the support 37 and to the front bar 44, as by spot welding, and the upper ends of said bars are secured to a frame (not shown) similar to that already described, it being appreciated that the articles are insertable from the tops of the stack defining means, pass downwardly therein under the influence of gravity, and are adapted to be discharged therefrom into a chute 49, when permitted to do so by the operation of control mechanism employed in connection with the invention.

Dispensing means are provided for dispensing the articles, and include a plurality of similar mechanisms, one for each stack, each requiring the presence of a proper coin or coins to release 55

the same, so that the selected article may be dispensed. Each of these mechanisms comprises a slide 50, having a flat bottom adapted to slidably rest upon the upper surface of the plate 34, and 5 having lugs 51 projecting downwardly through a slot 52 in the plate 34, and secured to the lugs 51 beneath the plate 34, by means of screws 53, is a metallic strip 54, which confines the slide 50 to its back and forth sliding movement in line 10 with one of the article containing stacks, the limit of rearward movement of the slide 50 being shown in Figure 4, and the limit of forward movement being shown in Figure 5, the slide being normally urged rearwardly by a spring 55. The upper surface of the slide 50 carries at its rear portion a platform member 56 adapted in one position of the slide 50 to support an article, indicated at 57, within its related stack, as shown in Figure 4, and in another position, shown in Figure 5, to push the dropped article rearwardly so as to flex a depending leaf spring 57a having its upper end attached to the top flange 39 of the support 37, and as the rear edge of the article drops the spring 57a flips the article into the 20 discharge chute 49 for delivery.

At the forward upper portion of the slide 50 there is provided a pair of transversely spaced coin pockets 58 and 59, open at the bottom, the pocket 58 in the present embodiment being of a 30 size to snugly accommodate a nickel, while the pocket 59 will similarly accommodate a dime. The outer side defining walls of the pockets 58 and 59 are cut out as at 60, for a purpose presently to appear. The forward walls of the pockets 58 and 59 are connected by a web 61, and to the web 61 is secured one end of an operating handle 62, which projects outwardly through an elongated slot 63 in the casing, and at its outer extremity has an operating knob 64.

Cooperating with the slide 50 are means which control movement of the slide 50, dependent upon the presence or absence of a coin in one or more of the coin pockets 58 and 59, the mechanisms for both pockets 58 and 59 being the same except for 40 their opposite disposition. Adjacent the coin pocket 58, there is provided an exploring finger 65, pivoted upon the plate 34, as at 66, and normally urged toward the slide 50 by a spring 67, said finger 65 being adapted to enter the cut-out 50 60 in the pocket 58 as the slide 50 moves forwardly, for the purpose of detecting the presence or absence of a coin therein. Fixedly carried by the finger 65 is a pin 68 adapted to enter a notch 69 formed in the side flange 70 on the slide 50, the parts being so positioned, that as the slide 50 is drawn forwardly, and a proper coin is present within the pocket 58, the coin first contacts the exploring finger 65 and moves said finger about its pivot in such manner as to prevent the pin 68 60 from entering, or appreciably entering, the notch 69, and under these conditions the slide 50 may be drawn freely forward. On the other hand, should a proper coin be absent from one or the other, or both of the coin pockets 58 and 59, the exploring finger 65 will enter more deeply into the pocket 58, and finding no coin, will permit the slide 50 to be drawn forwardly a sufficient distance to cause the pin 68 to fully enter the notch 69, and further forward movement of the slide 70 70 will be arrested because of binding action between the pin 68 and the wall of the notch 69 due to the different directions of movement of the parts; it is understood of course that the mechanism just described for the pocket 58, is duplicated in connection with the pocket 59.

By reason of the manner in which the pivoted finger 65 is mounted, it provides pivoted control means, the free end of which is normally disposed cross-wise of the path of movement of the notch 69, and the notch 69 and the pin 68 form coupling means, which, when no coin is present in the related coin pocket, first loosely engage, and then bind, to arrest movement of the dispensing means and of the free portion of the finger 65, along their independent divergent paths of movement. 10

In order to insure that the slide 50 cannot be moved rearwardly until it has moved to its extreme forward position, I provide a pivoted latch 71, carried by the slide 50, cooperable with a rack 72 formed on the upper surface of the plate 34, 15 the latch 71 being adapted to racket freely over the rack 72 in a forward direction, but engaging the rack 72 to prevent return movement until the limit of the forward movement of the slide is reached, a slot 73 being formed in the plate 34 20 which permits the latch 71 to drop thereinto, and change its position, and the latch 71 then permits free return movement of the slide 50.

For the purpose of preventing an article being shaken from its dropped position in the stack 25 when the slide 50 has been drawn partially forward, an abutment finger 74 is provided, working through a hole, indicated at 75, in the rear edge of the plate 34, and carried by a lever 76 pivoted, as at 77, to the under surface of the plate 34. The lever 76 has a cam surface 78, adapted to be engaged by an offset 79, formed in the strip 54 and movable with the slide 50, to depress the forward end of said lever 76, and to project the abutment finger 74 through the hole 75, said lever 76 30 having another cam surface 80 adapted to be engaged by the opposite end of said offset 79 upon return movement of the slide 50 to insure that the lever 76 is operated to withdraw the abutment finger 74 from its projected position. 40

Mechanism is also provided for dispensing packets of matches without charge, said means comprising an upright casing 81, polygonal in cross-section, the rear wall of which is interrupted as indicated at 82 (Figure 8), and the 45 front wall also is cut-out adjacent the bottom, as at 83, while the side and rear walls have bottom extensions forming ears 84, upon which the stack of matches within said casing is adapted to rest, the casing 81 being supported by a flange 50 85 secured to the flange 39 of the support 37. A leaf spring 86 is secured to the front wall of the casing and projects somewhat below the cut-out 83 of the front wall. A carrier 87 is provided for cooperation with the casing 81, and normally is 55 vertically aligned with the open bottom of said casing, said carrier being provided with an up-standing member 88 adapted to pass through the gap in the rear wall of the casing 81, between and above the ears 84, and the match packet is pushed 60 forwardly in such a way as to engage and flex the spring 86, and when the match packet is clear of the ears 84, the rear edge thereof drops, and the spring 86 then flips the match packet through the carrier 87 into the chute 49 for delivery. The 65 carrier 87 is reciprocably mounted upon a slide bar 89, and the latter is reciprocably carried by the plate 34, the outer end of said bar 89 having a cross-piece 90, adapted to be engaged by the webs 61 of adjacent slides 50, so that when either 70 slide 50 is operated, the slide bar 89 is carried forward also, ejecting a box of matches at the time the article is dispensed, a spring 91 serving normally to urge the slide bar 89 toward its rearward position.

Provision is also made for dispensing matches in which the mechanism is controlled by the insertion of a coin, this mechanism comprising a casing 32, carrier 33, ejecting means 34, similar to the casing 31, carrier 37, and leaf spring 36. In this embodiment the carrier 33 is mounted upon a reciprocably mounted slide bar 35 having an exterior handle 36 by manipulation of which the bar 35 may be reciprocated, a spring 37 normally urging the bar 35 in a rearward direction. Carried by the bar 35 is a coin pocket 38 adapted to receive a coin through a slot 39, and the side wall defining the coin pocket 38 has a cut-out 40 giving access to the interior of the pocket 38. Operable with the coin pocket 38 is a hooked exploring finger 41, pivotally mounted as at 42, and normally urged by a leaf spring 43, in a direction to enter the cut-out 40, it being evident that when the bar 35, carrying the coin pocket 38, is moved forwardly, the finger 41 will enter the cut-out 40, and is so proportioned that if a proper coin is present, the finger 41 will be pressed outwardly by the coin so as to clear the wall of the coin pocket without hooking therewith, and the coin pocket 38 permitted to pass; however, if no coin is present the finger 41 will move into the coin pocket far enough to hook into the wall defining the cut-out 40 and thus prevent further forward movement. As best shown in Figures 1 and 4, a plurality of coin chutes 44 are provided, one of said chutes 44 leading to each of the coin pockets 38 and 39, and entrance to each of the chutes 44 may be had through suitable slots 45 in the front of the casing. A money box 46 is provided for storing the coins when delivered thereto by any of the slides 35 through suitable slots 47 in the plate 34.

In operation, one desiring a package of cigarettes, will deposit a nickel in one of the chutes 44 leading to the coin pocket 38, and a dime in one of the chutes 44 leading to the coin pocket 39, of the selected slide 35 associated with the stack 48 in which the preferred brand of cigarettes is stored, whereupon the slide may be drawn forwardly through a pull upon the handle 36. As the slide 35 moves forwardly, with a proper coin in each of the pockets 38 and 39, the coin substantially filling each pocket 38 and 39 and exposed edgewise through the cut-out 40, will come into contact with an exploring finger 41 and swing the finger 41 about its pivot, and against the pressure exerted by the spring 43, thus moving the pin 48, carried by the finger 41, out of line with the notch 49, the finger 41 then being moved still farther in the same direction through contact with the side of the slide 35, as best shown at the left-hand forward portion of Figure 5. When the slide 35 has reached its forward limit of movement the coins in the pockets 38 and 39 fall through slots 47 in the plate 34 into the money box 46.

During forward movement of the slide 35, after the locking means have been passed, the pivoted latch 51, carried by the slide 35, will ratchet freely over the rack 52 but only so long as the slide 35 is moved in a forward direction, the latch 51 preventing rearward movement, until the platform member 56 has been shifted sufficiently to permit the lowermost article in the stack to drop to position so that rearward movement of the slide 35 under influence of the spring 55 will push the article against the spring 57a for delivery into the discharge chute 49.

Also during the free forward movement of the slide 35, the lever 56 is depressed due to coaction

of the cam surface 58 thereon with the offset 59 carried by the slide 35, so as to project the finger 54 through the hole 55, and thus provide an abutment which will prevent the articles being shaken into the chute 49 while the slide 35 is in its forward position, the cam surface 58 of the lever 56 being engageable by the offset 59 upon return movement of the slide 35 to effect positive retraction of the finger 54.

Forward movement of the slide 35 also serves to dispense packets of matches, without charge, simultaneously with delivery of a packet of cigarettes. This operation occurs due to engagement between the slide 35, after it gets free of the coin-controlled means, and the cross-member 50, the latter serving through the slide 35 to draw the carrier 37, normally positioned vertically beneath the stack of match packets in the casing 31, in a forward direction, causing the upstanding member 58 to move forwardly, and to move the lowermost packet of matches in a forward direction, the forward end of the match packet bearing upon the spring 36 and flexing the same, and when the carrier 37 has been drawn forwardly a sufficient distance, the forward portion of the match packet drops, and the spring 36 then flips the match packet through the carrier 37 and into the chute 49.

No forward movement of the slide 35 sufficient to dispense an article will be permitted to take place, however, unless proper coins are present in both of the pockets 38 and 39.

Should an attempt be made to draw the slide 35 forwardly without a coin present in the pocket 38, for instance, the exploring finger 35 enters the cut-out 40 of the pocket, and encountering no coin, enters relatively deeply therein, as the slide 35 begins its forward movement, and before the finger 35 can be displaced by engagement with the defining wall of the cut-out 40, the pin 48 on the finger 35, enters deeply into the notch 49 of the slide, and since movement of the finger 35 can take place only about the pivot 46, and the slide 35 is confined to rectilinear movement, the pin 48 binds in the notch 49 and arrests further forward movement of the slide 35, thereby preventing the slide 35 from releasing an article to be dispensed; the finger 35 would act in a like manner in connection with the pocket 39 should no coin be present therewithin. Of course, arrest of movement of the slide 35, prevents any movement thereof, which would be instrumental in dispensing free match packets.

The coin-controlled mechanism for controlling dispensation of match packets for which a charge is made operates as follows. When a coin is present in the coin pocket 38, the hooked exploring finger 41 is encountered by the coin as the slide bar 35 moves forwardly, and the coin pushes the finger 41 aside and unimpeded forward movement of the slide bar takes place, drawing with it a packet of matches to be discharged in the same manner described in connection with the free match packets. Should no coin be present, however, the finger 41 enters more deeply into the pocket 38, and instead of being pushed aside by the coin, hooks into the wall of the cut-out 40 and prevents further forward movement of the slide bar 35.

From the foregoing it will be understood by those skilled in the art that the embodiment herein disclosed accomplishes at least the principal object of the invention, that it has uses and advantages other than those herein particularly referred to, and that various other changes and

modifications may be made without departing from the spirit of the invention, and accordingly the embodiment disclosed herein is illustrative only and the invention is not limited thereto.

5. I claim:

1. A coin-controlled device of the character described, comprising: a supporting member having a slot therein communicating with a money box; dispensing means reciprocably mounted upon said supporting member; means for preventing unauthorized movement of said dispensing means, including a recess in said dispensing means, and a locking device pivotally mounted at one side of said dispensing means, normally urged athwart the path of said dispensing means, and having locking means spaced from its pivot and disposable within the recess of said dispensing means to arrest movement of the same; and a coin receiver carried by said dispensing means and positioned to carry a coin substantially parallel to the direction of movement of said dispensing means, said coin receiver being cut out along its advance edge to present a coin substantially at right angles to said locking device for edgewise engagement with said locking device to shift the locking device to a position to allow unimpeded movement of said dispensing means, and said coin receiver being open at the bottom and adapted to register with the slot in said supporting member after said dispensing means has passed said locking device.

2. A coin-controlled device, comprising: dispensing means movable toward a predetermined position, and having locking elements at opposite sides thereof, each movable therewith along a predetermined path; a first pivoted control means having its pivot disposed at one side of the path of movement of the adjacent locking element, and having a free portion extending cross-wise of said path, and provided with a locking element inter-engageable in one position with the adjacent locking element of said dispensing means, to connect the free portion of said pivoted means and said dispensing means; a second similar pivoted control means, similarly mounted at the opposite side of said dispensing means, extending in an opposite direction to said first pivotal control means, and cross-wise of the path of, and having a locking element engageable with, the opposite adjacent locking element of said dispensing means; and coin-controlled means for controlling the position of each of said pivoted control means.

3. A coin-controlled device, comprising: dispensing means movable toward a predetermined position along a predetermined path; means movable with said dispensing means and forming a coin pocket adapted to present a coin vertically edgewise along the direction of movement of said dispensing means, said coin pocket being cut out along its forward edge; and pivoted control means swingable in a plane substantially normal to the broad face of a coin disposed in said pocket, having its pivot disposed at one side of the path of movement of said dispensing means, and having a free portion extending cross-wise of the path of said dispensing means, the latter and the free portion of said pivoted means having locking elements interengageable in one position to connect the free portion of said pivoted means and said dispensing means, said pivoted means having a portion adapted to enter the cut-out of said coin pocket, and operable through engage-

ment by a coin in said pocket to prevent inter-engagement of said locking elements.

4. A coin-controlled device, comprising: a first dispensing means movable toward a predetermined position and having a locking element movable therewith along a predetermined path; a similar second dispensing means mounted adjacent to, but spaced from, said first dispensing means; a first pivoted control means having its pivot disposed between said first and second dispensing means, and at one side of the path of movement of the locking element of said first dispensing means, and having a free portion extending cross-wise of the path of said locking element of said first dispensing means, and provided with a locking element, said locking elements being interengageable in one position to connect the free portion of said pivoted means and said first dispensing means; and a second pivoted control means, similar to said first pivoted control means, and cooperable with said second dispensing means, said second pivoted control means being mounted to move about the same pivot as said first pivoted control means; and coin-controlled means for controlling the position of said pivoted control means.

5. A coin-controlled device, comprising: a first dispensing means movable toward a predetermined position and having a locking element movable therewith along a predetermined path; a similar second dispensing means mounted adjacent to, but spaced from, said first dispensing means; a first pivoted control means having its pivot disposed between said first and second dispensing means, and at one side of the path of movement of the locking element of said first dispensing means, and having a free portion extending cross-wise of the path of said locking element of said first dispensing means, and provided with a locking element, said locking elements being interengageable in one position to connect the free portion of said pivoted means and said first dispensing means; a second pivoted control means, similar to said first pivoted control means and cooperable with said second dispensing means, said second pivoted control means being mounted to move about the same pivot as said first pivoted control means; a single spring for urging said pivoted control means in opposite directions; and coin-controlled means for controlling the position of said pivoted means.

6. A coin-controlled device, comprising: dispensing means movable toward a predetermined position along a predetermined path; means movable with said dispensing means and forming a coin pocket adapted to present a coin vertically edgewise along the direction of movement of said dispensing means; and pivoted control means swingable in a plane substantially normal to the broad face of a coin disposed in said pocket, having its pivot disposed at one side of the path of movement of said dispensing means, and having a free portion extending cross-wise of the path of said dispensing means, the latter having an arcuate notch therein, and the free portion of said pivoted means having projecting means engageable in said notch to connect said free portion of said pivoted means and said dispensing means, said pivoted means having an extension extending beyond said projecting means, and arranged in line with a coin when in said pocket, to be engaged by said coin to prevent entrance of said projecting means into said notch.

ANDREW GORRETTA.
